UNITED STATES PATENT OFFICE.

FRANK E. LULL, OF CHICAGO, ILLINOIS.

ELECTRICALLY-CONTROLLED VALVE.

Application filed July 17, 1925. Serial No. 44,387.

My invention relates to improvements in electrically controlled valves, and it consists in the combinations, constructions and arrangements herein described and claimed.

5 An object of my invention is to provide an electrically controlled valve principally for controlling the flow of gas to a burner for drying paper, which burner must be in actuation during all the time that the presses 10 are in operation.

My invention pertains to mechanism for automatically opening the valve so as to turn on the gas when the motor for operating the presses is placed in operation.

15 A further object of my invention is to provide an electrically controlled valve of the character described which is entirely automatic in operation.

20 A further object of my invention is to provide an electrically controlled valve which is simple in construction, durable and thoroughly practical for the purpose intended.

Other objects and advantages will appear 25 in the following specification, and the novel features of the invention will be particularly pointed out in the appended claim.

My invention is illustrated in the accompanying drawing forming part of this application, in which—

Figure 1 is a front elevation of an embodiment of my invention, a part thereof being in section with the casing removed, and

30 Figure 2 is a top plan view of the device illustrated in Figure 1 with the casing in place.

In carrying out my invention I make use 35 of an electric motor 1 which is connected to an electric power source 2 through lead wires 3. A manually actuated switch 4 is connected in series with one of the lead wires 3 shown in Figure 1.

40 My improved electrically controlled valve 45 consists in a pair of solenoid coils 5 connected in series and disposed concentric with a tubular member 6 of insulating material. The coils 5 have their terminals connected by means of conductors 7 and 8 to the terminal 9 of the motor 1 disposed adjacent to the switch 4 and to the wire of opposite polarity extending from the power source 2.

A laminated core 10 is disposed about the solenoid coils 5 and secured to the tubular member 6 by encompassing the tubular member 6 with certain of the leaves of the core.

The core 10 is bound together and to a casing consisting of two parts 11 and 12 respectively by the provision of screws 13 having nuts 14 projected through the parts of 60 the casing 11 and 12 and through the core.

A stationary central laminated core piece 15 is disposed within the tubular member 6 at the upper end thereof and is secured thereto by a bolt 16 projected diametrically 65 through the tubular member and through the core.

A solenoid core piece 17 is slidably mounted within the tubular member 6. The upper end of the tubular member 6 is closed by 70 means of a threaded metal plug 18 having a threaded aperture 19 therethrough into which a gas pipe 20 is threaded. The gas pipe 20 is connected with a source of gas supply.

75 The lower end of the tubular member 6 has a metal chamber 21 secured thereto and communicating with the interior of the tubular member. A member 21 having a valve seat 22 communicates with the interior of 80 the chamber 21 and is secured thereto by means of threads 23 on the exterior wall of the member 21 and on the interior walls of the end opening provided through the bottom wall of the chamber 21. A valve 85 member 24 is disposed within the registering members 21 and 21. The valve member 24 is secured by means of a rod 25 to the solenoid core 17, so that when the solenoid core 17 is drawn upwardly, as by energization of 90 the solenoid coils 25, the valve 24 will be lifted from its seat 22.

The valve member 24 has a substantially tubular port 26 at the lower end thereof communicating with the interior of the 95 member 21 beneath the valve as shown in dotted lines at 26.

100 Openings 27 are provided transversely through the side walls of the lower portion of the valve member 24, whereby gas may pass from the chamber 21 through the openings 27 and by way of the tubular portion 26 to the interior of the member 21.

105 The lower portion of the member 21 is connected by means of a pipe 28 to a gas burner 29. At 30 I have illustrated paper disposed over the burner 29 as when the paper is moved over the burner during the drying process. It should be remembered that the paper 30 is in motion during all 110 times when the motor 1 is in operation. The solenoid coils and the motor are operated

simultaneously by closing the switch 4, thus the burner 29 will be in operation. A connection 31 leads to a pilot light 32.

From the foregoing description of the various parts of the device the operation thereof may be readily understood. When the motor 1 which operates the press is placed in operation by closing the switch 4, current will also be conducted to the solenoid coils 5 which will become energized to cause the solenoid core 17 to rise, thus opening the valve 24. Gas may then pass through the tubular member 6, through the chamber 21 and to the burner 29 through the pipe 28 so as to dry the paper 30.

I claim:

An electrically controlled valve comprising

ing a gas burner, a valve chamber having a valve seat, a gas-conveying conduit connecting said chamber with said burner, a valve, a cylindrical guide integral with said valve and having openings therein, said guide slidably disposed in said chamber, a tubular member connected to said valve chamber, a solenoid core piece slidably mounted within the tubular member and being operatively connected to said valve, a solenoid coil disposed about said tubular member, a gas pipe for connecting gas to said tubular member, a pilot light disposed adjacent to said gas burner, and a by-pass connecting said pilot light with said valve chamber at a point above the valve.

FRANK EUGENE LULL.
